EASILY CLEANED HAIR COMB

BACKGROUND OF THE INVENTION

Hair combs, as conventionally made, have fixed teeth with flat confronting sides which, cumulatively, provide a large area on which foreign matter collects. It is exceedingly difficult to clean this area so that the collection of foreign matter becomes a breeding ground for bacteria which, when the comb is used, is transferred to the hair, and reinfection occurs the first time the comb is used after a shampoo.

Various attempts have been made to provide a comb which can be readily cleaned, by mounting the teeth so that they may be rotated so as to expose the normally confronting areas of the teeth. For example, U.S. Pat. No. 2,808,062 discloses a comb with freely rotatable teeth of circular cross section. Another patent, U.S. Pat. No. 1,340,946, provides a pinion at the mounted end of each tooth and a rack drive to rotate the teeth. In both of these constructions the teeth are symmetrical about their longitudinal axes and therefore in order to withstand the bending loads incidental to combing must be exceptionally strong or be relatively large in diameter. As a practical matter, a comb so constructed must be too coarse to be useful.

Another approach to the problem is disclosed in U.S. Pat. No. 2,401,143. Here each tooth includes a cylindrical journal portion having a flat combing portion extending from one end and a lever projecting radially from the other end thereof. The teeth are simultaneously turned by a reciprocable member. However, the problem inherent in the previously indicated patents is not overcome, for if the journal portions are made small enough to permit acceptable tooth spacing, the teeth must be made of metal at substantial cost to have the necessary strength.

A further problem inherent in the listed patents and insofar as known, in all attempts to provide a rotatable tooth comb is due to the fact that the teeth must be made individually and individually assembled in the comb at substantial labor cost.

SUMMARY OF THE INVENTION

The present invention provides a solution to the problems previously encountered in the manufacture of combs having turnable or rotatable teeth and is summarized in the following objects:

First, to provide an easily cleaned hair comb wherein the teeth are rotatable in unison in one direction from an initially parallel relation to an angular relation in which at least half of the normally confronting sides are exposed, and are rotatable in the opposite direction to expose the remaining half of the confronting sides, thereby to permit complete cleaning of the teeth.

Second, to provide an easily cleaned hair comb which, because of the movement indicated in the preceding object, the teeth may have a width-to-thickness ratio and a spacing comparable to a standard fixed tooth comb.

Third, to provide an easily cleaned comb in which the teeth are joined integrally by hinge elements in such a manner that the teeth and connecting hinge elements may be injection molded as a single unit; whereby, although the teeth are turnable rather than fixed, the manufacturing cost of the comb is minimal.

Fourth, to provide a comb which is so readily and quickly manipulated for cleaning as to make feasible, the cleaning of the comb after each use.

DESCRIPTION OF THE FIGURES

FIG. 1 is a side view, showing one embodiment of the easily cleaned hair comb, shown in its assembled condition.

FIG. 2 is a side view thereof, shown disassembled.

FIG. 3 is an enlarged fragmentary view, taken through 3-3 of FIG. 1, with the comb frame in section and the comb structure in plan.

FIG. 4 is a fragmentary sectional view, taken through 4-4 of FIG. 3.

FIG. 5 is an enlarged fragmentary sectional view, taken through 5-5 of FIG. 3, with the comb frame shown in elevation.

FIG. 6 is an enlarged fragmentary plan view of the comb structure, corresponding to FIG. 3, but with the comb frame omitted.

FIG. 7 is a sectional view of the comb structure, taken through 7-7 of FIG. 5, showing the teeth in parallel relation; that is, in their combing position.

10 FIG. 8 is a fragmentary plan view of the comb structure, corresponding to FIG. 6, but showing the teeth in one of their angular positions assumed for cleaning purposes.

15 FIG. 9 is a fragmentary sectional view, corresponding to FIG. 7, but showing the teeth in one of their angular cleaning positions.

FIG. 10 is another fragmentary sectional view, corresponding to FIG. 7, showing the teeth in their opposite angular cleaning position.

20 FIG. 11 is a sectional view of the comb structure, taken through 11-11 of FIG. 2, showing one of the teeth in elevation.

FIG. 12 is a fragmentary side view of the comb frame modified to form a turning key.

25 FIG. 13 is a transverse sectional view, taken through 13-13 of FIG. 12.

FIG. 14 is a fragmentary side view of the comb structure modified to provide key receiving notches.

20 FIG. 15 is a transverse sectional view, taken through 15-15 of FIG. 14.

30 FIG. 16 is a partial side view, partial sectional view, showing a modified form of the easily cleaned hair comb.

FIG. 17 is an enlarged sectional view, taken through 17-17 of FIG. 16.

35 FIG. 18 is an enlarged fragmentary sectional view, taken through 18-18 of FIG. 16, with the comb structure shown in plan and with the teeth in parallel combing position.

FIG. 19 is a similar enlarged fragmentary sectional view, showing the teeth in one of their cleaning positions.

40 FIG. 20 is a similar fragmentary sectional view, showing the teeth in their other cleaning position.

FIG. 21 is an enlarged fragmentary sectional view, taken through 21-21 of FIG. 16, showing the teeth in their combing position.

45 FIG. 22 is a fragmentary sectional view, taken in the same plane as FIG. 21, showing the teeth in one of their cleaning positions.

FIG. 23 is a corresponding fragmentary sectional view, showing the teeth in their other cleaning position.

50 Reference is first directed to FIGS. 1 through 11. The construction here illustrated includes a comb frame 1, which in turn includes a back member 2 and a pair of end teeth 3 at the extremities thereof.

A set of orientation members 4 in the form of stub teeth project from the back member 2 between the end teeth 3.

The comb frame 1 receives a comb structure 5 which includes a pair of mounting bars 6 adapted to be disposed along opposite sides of the comb frame, between the end teeth 3. The mounting bars cover the sides of the orientation members 4.

60 A set of combing teeth 7 is provided. Each tooth includes an upper end portion 8, the lateral sides of which are joined to the two mounting bars 6 by hinge webs 9.

65 When the mounting bars 6 are positioned along opposite sides of the orientation members or stub teeth 4, the stub teeth fit between the upper portions 8 of the combing teeth 7 so as to hold the combing teeth in parallel relation, in the manner of a conventional comb. In order to retain the combing teeth in this position, the mounting bars are provided near their extremities with retention keys 10, which are received in retention grooves 11. The lower ends of the grooves 11 are beveled so that the mounting bars 6 may be pressed downwardly with respect to the back member of the comb frame so that the

70 comb structure may be separated from the comb frame.

75

When the comb structure 5 is separated from the comb frame 1, the mounting bars 6 may be moved longitudinally relative to each other in opposite directions, one such position being shown in FIGS. 8 and 9. With reference to FIG. 9, it will be noted that the areas indicated by 12 and 13 of each tooth are exposed for cleaning. When the mounting bars 6 are moved to their opposite position, the teeth are moved to the position shown in FIG. 10, exposing the areas 14 and 15 thereof. The spacing between the teeth and the width of the teeth are so proportioned that the entire surface of each tooth is exposed when the teeth are positioned as shown in FIG. 9 and then moved to the position shown in FIG. 10. Thus, the teeth are partially cleaned when in the first position shown in FIG. 9, and the cleaning is completed upon movement of the teeth to the position shown in FIG. 10.

It will be noted that the comb structure may be injection molded as a unit. The mounting bars 6, combing teeth 7 and hinge webs 9 all being integrally connected.

In order to facilitate relative longitudinal movement of the mounting bars 6, a series of ribs 16 are provided.

Reference is now directed to FIGS. 12 through 16. In the construction here illustrated, the side bars 6 of the comb structure are provided with opposed notches 6a and the comb frame 1 is provided at its normally top side with side recesses 1a which form a key web 1b.

The key web 1b is used to effect relative movement of the bars 6 by inserting the key web into the notches 6a then turning the comb frame relative to the comb structure causing the notches 6a to be displaced. It is preferred, if the notches 6a are provided, to make the side bars 6 heavier.

Reference is now directed to FIGS. 17 through 23. In the construction shown in FIGS. 1 through 11, the comb structure 5 is separated from the comb frame for purposes of cleaning the comb structure. In the modified construction, the comb structure remains in the comb frame during the cleaning operation.

The modified construction includes a comb frame 17, having a back member 18 and a pair of end teeth 19. Formed in the back member and extending between the end teeth 19, is a longitudinal channel 20, one side of which has a series of fulcrum notches 21.

The modified construction includes a comb structure 22, having a mounting bar 23 which fits within the channel 20 in opposition to the fulcrum notches 21. A set of combing teeth 24 are provided, having journal portions 25 at their upper ends which pivot in the fulcrum notches 21. The journal portions 25 are joined to the mounting bar by hinge webs 26.

The mounting bar 23 is provided with one or more cam bosses 27 which cooperate with cam slots 28 formed in the confronting wall of the channel 20. The cam bosses and their mating slots are so shaped that when the mounting bar 23 is moved longitudinally in the channel 20, the mounting bar 23 is forced toward the fulcrum notches 21 to permit pivotal or turning movement of the combing teeth in the manner permitted by the hinge webs 26.

In order to effect the desired longitudinal movement of the mounting bar, the mounting bar is provided with an operating boss 29 which projects through a clearance slot 30 in the back member 18 of the comb frame.

When the mounting bar 23 is moved from one extreme position to the other, the combing teeth 24 are caused to pivot from the position shown in FIG. 22 to the position shown in FIG. 23 through the position shown in FIG. 21. As in the first described structure, at least half the surface of each tooth is exposed when the teeth are in the position shown in FIG. 22, and the remaining surface of each tooth is exposed when in the position shown in FIG. 23. Normally, the cam bosses 27 and their cam slots 28 hold the teeth in parallel or combing position, as shown in FIG. 21.

It will be noted that as in the first described structure, the combing teeth 24, hinge webs 26 and mounting bar 23 may be readily formed by injection molding as a single part.

While particular embodiments of this invention have been shown and described, it is not intended to limit the same to the details of the constructions set forth, but instead, the invention embraces such changes, modifications and equivalents of the various parts and their relationships as come within the purview of the appended claims.

I claim:

1. An easily cleaned hair comb, comprising:
  - a. a comb frame;
  - b. a plurality of combing teeth mounted therein and having normally confronting sides;
  - c. pivot means for each tooth permitting limited turning thereof; and
  - d. means for turning said teeth in unison in one direction to expose for cleaning portions of said normally confronting sides and for turning said teeth in unison in the opposite direction to expose for cleaning the remaining portions of said normally confronting sides.
2. A hair comb, as defined in claim 1, wherein said pivot means are individual hinge webs integrally connecting each tooth to said turning means.
3. A hair comb, as defined in claim 1, wherein:
  - a. said turning means include a pair of oppositely mounted moving bars at opposite sides of said teeth; and
  - b. said pivot means includes a pair of hinge webs integrally joining each tooth to said bars.
4. A hair comb, as defined in claim 1, wherein:
  - a. said turning means includes a bar at one side of said teeth and an opposed series of fulcrum notches for said teeth; and
  - b. said pivot means includes a hinge web integrally joining each tooth to said bar and journal portions formed on said teeth and received in said fulcrum notches.
5. A hair comb, as defined in claim 3, wherein:
  - a. said comb frame includes means fitting between said teeth at the hinge web ends thereof to retain said teeth in parallel relation; and
  - b. said combing teeth and bars are removable as a unit from said comb frame to permit opposed movement of said bars thereby to turn said teeth.
6. An easily cleaned hair comb, comprising:
  - a. a frame of combing teeth;
  - b. at least one flexible integral hinge extending from one side of each tooth at one end thereof;
  - c. and at least one mounting bar integrally connected to said flexible hinges; and
  - d. means for turning said teeth in unison by movement of said bar relative to said frame between parallel positions in which portions of said teeth are in confronting relation, and angular positions in which said confronting portions are exposed for cleaning.
7. A hair comb, as defined in claim 6, wherein:
  - a. a pair of said bars are provided and a pair of said hinges connect each tooth to said bars; and
  - b. said bars form said tooth turning means.
8. A hair comb, as defined in claim 7, wherein:
  - a. said bars are provided with key receiving notches; and
  - b. a key dimensioned to be received in said notches and adapted to turn thereby to cause relative longitudinal displacement of said bars.
9. A hair comb, as defined in claim 6, wherein:
  - a. means forming a series of fulcrum notches is disposed opposite said bar, and said teeth include journal elements fitting said notches; and
  - b. said bar and notches means form said tooth turning means.
